UNITED STATES PATENT OFFICE.

ALONZO M. GANNAWAY, OF MCCOY, KENTUCKY.

COMBINED EXTENSIBLE AND FOLDABLE TABLE.

1,210,635.

Specification of Letters Patent. Patented Jan. 2, 1917.

Application filed June 15, 1915. Serial No. 34,211.

To all whom it may concern:

Be it known that I, ALONZO M. GANNAWAY, a citizen of the United States, residing at McCoy, in the county of Breckenridge and State of Kentucky, have invented certain new and useful Improvements in Combined Extensible and Foldable Tables, of which the following is a specification.

The present invention relates to a new and improved table and the principal object of the invention is to provide a device of this nature that is both extensible, and foldable, and thus by reason of its extensibility it is especially adapted for household uses as a dining table, etc., and being foldable only a minimum space will be utilized when it is not in use.

Another object is to provide a table of the above nature wherein the top structure is foldable about a central longitudinal axis whereby when the same is in a folded position it will assume a neat and compact form, hence not only proving advantageous for minimizing the space utilized, but greatly facilitating handling thereof during the course of shipping.

A further object resides in the provision of a device of the foregoing character wherein the parts are coöperatively so arranged to permit free and easy movement whereby the table may be extended and additional leaves inserted, and folded with but little exertion on the part of the operator.

A still further object is to provide a device of the type which is highly practical and efficient and which consists of but a few simple parts whereby it is believed that the same may be manufactured at a comparatively low cost.

Various other objects and advantages will become apparent during the following description.

The above and other objects which will become apparent, are accomplished by such means as are shown in their preferred form in the accompanying drawings, described in the following specification and then more specifically pointed out in the appended claims.

In the accompanying drawings wherein like characters designate like parts throughout the several views; Figure 1 is a central longitudinal sectional view of my improved table showing the same in a folded position. Fig. 2 is a bottom plan view of my invention showing the same in an open po-

sition. Fig. 3 is a vertical sectional view taken on line 3—3 of Fig. 1. Fig. 4 is a similar view taken on line 4—4 of Fig. 1. Fig. 5 is a detail view of a bracket that is employed. Fig. 6 is a detail view. Fig. 7 is a detail view of one improved bracket that is employed.

In the drawings, the numeral 10 designates the base member of the device which carries a plurality of vertically arranged sleeves 11 adjacent its respective ends and fixedly supports a suitably formed brace member 12 through the medium of yokes 13. The base member is supported by a plurality of legs 14 which are provided with yokes 15 that in turn carry fastening members 16; the fastening members passing through the sleeves 11 of the base member and thus holding the legs 14 in pivotal relation therewith. The said supporting legs may be provided with casters 17 when reducing my invention to practice, however this is an entirely arbitrary feature and it is to be understood that other means may be substituted if it is desired.

A comparatively long tubular shaft 18 is supported by a brace member 12 and may have connection therewith through the medium of the fastening members 19 and, in turn slidably carries a pair of stub shafts 20 and 21 respectively which project from the respective ends thereof as illustrated in Figs. 1 and 2. A plurality of half-leaves 22 and 23 are now provided, to the inner end of which is attached a bracket similar to that illustrated in Fig. 7 of the drawings. This particular bracket which has been illustrated, consists of a base plate 24 which is fixed to the under side of the half-leaf, and carries an eyelet 25 for embracing either the shaft 18 or the stub shafts 20 or 21. Upon reference to Fig. 2 of the drawings it will be noted that the brackets on certain of the half-leaves embrace the shaft 18 while others engage the stub shafts 20 and 21 respectively, thus when the said half-leaves are arranged in a horizontal position a comparatively neat table-top will be provided. It will also be understood that each of the half-leaves is held in pivotal relation with respect to the shaft 18 and the respective stub shafts 20 and 21 thus allowing the same to be moved into the position illustrated in Figs. 1 and 3.

To the under face of each of the half-leaves is secured a bracket 26 which are ar-

ranged in alinement as shown in Figs. 1 and 2 so as to receive the hollow shafts 27, the said hollow shafts tending to retain the half-leaves so that they may be more readily operated uniformly. The opposite hollow shafts 27 receive a supplemental shaft 28 whereby they may be moved relative to each other in consistence with the lengthening of the table top without destroying the unity 10 of the respective half-leaves.

The bracket shown in Fig. 6 consists of a pair of removable sections 29 and 30 the same being bent as at 21 to embrace the horizontal portion of the supporting legs 14, and again bent as at 32 to embrace the inner ends of the arms 33. The brackets are arranged on the horizontal portions of the supporting legs adjacent their connection with the jaws 15 and by reason of their novel 15 construction, are free to move on the said horizontal portion of the supporting legs in the manner desired and as hereinafter set forth. The arms 33 which have pivotal connection with the said brackets through the medium of the fastening members 34 are slightly curved adjacent their outer ends as at 35 and carry inwardly projecting lugs 36. Now, when the half-leaves are in a horizontal position as shown in Fig. 2 the said 20 lugs 36 on the arms 33 may be received in the outer ends of the respective shafts 27 so as to support the outer ends of the half-leaves in an obvious manner. Of course, it is to be understood that means in the form 25 of stop members 37 may be carried by the said arms 33 in order that the spreading of the supporting legs will cause similar movement thereof and thus facilitate the operation of the device.

In Fig. 5 an improved form of bracket is illustrated which is designed to be used on auxiliary half-leaves, for the purpose of supplanting the form of bracket shown in Fig. 7 and permit easy and free removal or attachment of the auxiliary half-leaves when required.

In the operation of my improved table it will be assumed that the parts are in the position shown in Fig. 2, as in ordinary use. Now, in order to fold the table, the curved 50 portions 35 of the arms 33 are operated so as to withdraw the lugs 36 from the outer ends of the shafts 27, after which the supporting legs 14 are moved toward each other thus 55 withdrawing support from the outer ends of the half-leaves and allowing the latter to move slowly into the position shown in Figs. 3 and 4. When in this closed position it will 60 be recognized that the table will take up only a minimum amount of space and thus it is believed that the same will prove very advantageous for household uses.

If the table is to be lengthened, the auxiliary leaves, (not shown) are brought into 65 use after the stub shafts 20 and 21 have been

properly manipulated. By lengthening the main shaft 18 through the medium of the respective stud shafts, the shafts 27 will have to be moved as will the arms 33. However this operation appears to be readily obvious and therefore a further explanation is deemed unnecessary.

In reducing my invention to practice I find that the form referred to herein as the most practical and preferred embodiment is 75 the most efficient, but realizing that certain conditions will necessarily vary in concurrence with the adoption of my device I desire to emphasize the fact that various minor changes in the details of construction and in 80 the proportion of parts may be resorted to when required without sacrificing any of the advantages of my invention as defined in the appended claims.

Having thus fully described my invention, 85 what I claim as new and desire to secure by Letters Patent is:

1. A table of the class described including a base member, a plurality of supporting legs movably connected with said base member, a brace member carried by said base member, a plurality of oppositely arranged half-leaves pivotally connected to said base member, whereby they may be moved to assume a substantially vertical position and means carried by said supporting legs to support said half-leaves in a substantially horizontal position as and for the purpose specified.

2. A table of the class described including a base member, a plurality of supporting legs having connection with said base member and movable horizontally with respect thereto, a hollow shaft supported above said base member, said hollow shaft carrying a plurality of stub shafts which project from each end thereof, a plurality of half-leaves, said half-leaves provided with brackets, certain of said brackets embracing said shaft, other of said brackets 100 embracing said stub shafts, whereby said half-leaves may be moved to assume a substantially vertical position, and means carried by said supporting legs for supporting said half-leaves in a substantially horizontal position, as and for the purpose specified.

3. A table of the class described including a base member, a plurality of supporting legs movably attached thereto, a hollow shaft supported above said base member and extending longitudinally with respect thereto, stub shafts carried by said shaft and projecting from each end thereof, a plurality of oppositely arranged half-leaves, brackets carried by said half-leaves, certain of said 110 brackets embracing said shaft, other of said brackets embracing said stub shafts, whereby said half-leaves may be moved relative to each other when assuming substantially vertical position, other brackets carried by 115

5 said half-leaves adjacent their outer ends, hollow shafts supported by said last mentioned brackets, auxiliary shafts carried by said last mentioned hollow shafts, arms adjustably supported on said supporting legs, and lugs carried by said arms for reception in the outer ends of said last mentioned hollow shafts whereby said half-leaves may be supported in a substantially horizontal position, as and for the purpose specified.

10 4. A table of the character described including a base member provided with a plurality of vertically arranged sleeves, a plurality of supporting legs provided with 15 means for engagement with said sleeves whereby they may be moved relative to said base member, a brace member fixed to said base member, a hollow shaft carried by said brace member, stub shafts arranged in said 20 hollow shaft and projecting from each end thereof, a plurality of oppositely arranged half-leaves, said half-leaves provided with brackets for engagement with said hollow

shaft, other oppositely arranged half-leaves having brackets for engagement with said 25 stub shafts, said half-leaves being oscillatable about said hollow shaft and said stub shafts whereby they may be folded to assume a substantially vertical position, other brackets carried by said half-leaves and supporting other hollow shafts, auxiliary shafts carried by said last mentioned hollow shafts, an arm adjustably mounted on each of said supporting legs, the outer ends of said arms being curved upwardly and provided with 30 an inwardly projecting lug, said lugs entering the outer ends of said last mentioned hollow shafts whereby said half-leaves may be supported in a substantially horizontal position, as and for the purpose specified.

35 5. In testimony whereof I affix my signature in presence of two witnesses.

ALONZO M. GANNAWAY.
